JOHN R. FLEMING, OF CLEVELAND, AND EDMUND M. WINEGAR, OF WILLOUGHBY, OHIO,
ASSIGNORS TO THE OHIO RUBBER COMPANY, OF CLEVELAND, OHIO, A CORPORATION
OF OHIO

BEAD STRIP ATTACHING PRESS

Application filed February 6, 1931. Serial No. 514,025.

This invention relates to machines of the kind known as punch presses, and more particularly to a machine of this type for attaching covering or sheathing material to flange or bead portions of a body, such as a vehicle running board.

An object of the invention is to provide an improved machine of the kind mentioned for rapidly and uniformly attaching covering or sheathing material in strip or sheet form to a portion of a preformed body.

Another object of this invention is to provide a machine of the kind mentioned, having a set of punches adapted to be moved into engagement with covering material to secure the same to a body by pressing portions of the covering material into openings in the body.

Another object of this invention is to provide a machine of the kind mentioned, in which sets of punches having intersecting paths of movement are actuated in succession to secure covering material to a body.

A further object of this invention is to provide a machine of the kind mentioned, in which sets of punches having intersecting paths of movement are adapted to be moved into engagement with a sheet metal member to secure the same to a body.

The invention may be further briefly summarized as consisting in certain novel combinations and arrangements of parts herein-after described and particularly set out in the appended claims.

In the accompanying sheets of drawings,

Figure 1 is a side elevation of a punch press embodying our invention.

Fig. 2 is a sectional plan view taken on line 2-2 of Fig. 1.

Fig. 3 is a sectional plan view taken on line 3-3 of Fig. 1.

Fig. 4 is a transverse sectional elevation of the slide taken on line 4-4 of Figs. 1 and 3.

Fig. 5 is a transverse sectional elevation of the slide taken on line 5-5 of Figs. 1 and 3.

Fig. 6 is a partial sectional elevation taken on line 6-6 of Fig. 2.

Fig. 7 is a partial sectional elevation showing one of the special corner punches and

illustrating the operation performed thereby.

Figs. 8 and 9 are detail elevational views of one of these special corner punches.

Fig. 10 is an end elevational view of a running board in inverted position with the bead strips in place ready for the punching operations.

Fig. 11 is a transverse sectional elevation taken at a point intermediate the ends of the same running board after the punching operations have been performed thereon.

Fig. 12 is a detail view showing the shape of the slide actuating cam, and

Fig. 13 is a similar detail view showing the shape and relative positions of the punch actuating cams.

In the drawings, to which detailed reference will presently be made, we have shown our invention embodied in a machine of the punch press type for rapidly and uniformly attaching metallic covering material in strip form, to flange or bead portions of preformed bodies, such as composite vehicle running boards, but it should be understood that our invention may be embodied in various machines for performing similar operations on other materials and on bodies of other shapes or forms.

Before proceeding with a detailed description of the machine of our invention, brief reference will be made to the vehicle running board, which, in this instance, constitutes the preformed body, and to the operations to be performed thereon. This running board, which is disclosed in United States Patent No. 1,784,781, granted December 9, 1930, comprises a sheet metal body 15 having flanges 16 and 17 depending, respectively, along the back and ends thereof for reinforcing the running board and securing the same to portions of the vehicle, and a rubber covering 18 vulcanized to the metal body so as to extend down upon the depending front flange 19. At the point of connection of the back and end flanges with the metal body the metal is bent to form the upstanding longitudinally extending beads 20 and 21. The rubber covering which is vulcanized to the metal body covers substantially the entire up-

per surface thereof leaving exposed the upstanding beads 20 and 21, against which, edges of the covering abut. To provide a finish for these upstanding beads such that they will resist wear and corrosion, and will impart to the board an attractive appearance, they are fitted respectively with covering or sheathing members 22 and 23. These members are of suitable material such as chromium plated zinc, and are applied to the beads by means of the press which we have devised. In securing these members to the respective beads, portions of the members are bent or crimped around portions of the running board body by successive operations performed by the sets of punches of the press now to be described in detail.

In general this press comprises a frame 24, which supports a bed plate 25 in substantially horizontal position, and a reciprocable slide 26 which is guided by the portions of the frame uprights 27 extending above the bed plate. A die 28 which is secured to the bed plate 25, is provided with a recess of such shape and form as to receive a running board in an inverted position, as shown in Fig. 2 of the drawings, ready to be operated upon by the sets of punches which are moved into engagement with the work in succession.

Before the running board is placed in the recess of the die, the strips 22 and 23 are applied to the beads 20 and 21 by the press operator. These strips, as shown in Figs. 10 and 11 of the drawings, are somewhat rounded in cross-sectional shape to correspond with the rounded portion of the upstanding beads which they are to cover. In applying the strips to the beads of the running board, the operator first hooks the rounded portion of the bead strip 22 over the upstanding bead 20 extending along the rear edge of the running board body. In a similar manner the operator then applies the bead strips 23 to the end beads 21, by hooking their rounded portions over these beads. As indicated in Figs. 10 and 11 that end of each bead strip 23 which is nearest the rear flange 16 of the running board, is formed with an extension or tail portion 29 which overlaps the extreme end portion of the previously applied bead strip 22. When these strips have been applied to the rear and end beads of the running board in the manner described, they will occupy the relative positions shown in Figs. 6 and 10, with the securing tangs or tongues 30 of the bead strip 22 registering with the longitudinally spaced slots 31 provided in the rear flange 16 of the running board body, and with similar securing tongues 32 of the end bead strips 23 registering with the spaced slots 33 provided in the end flanges 15 of the running board body.

When the bead strips have been applied to the running board in the manner just de-

scribed, the operator places the running board in the recess of the die 28 in inverted position, as indicated in Fig. 2, ready for the punching operations to be performed thereon. When the running board is in position in the die recess the tongues 30 of the rear bead strip 22 register with the punches of a row or series of horizontally movable punches 34 extending in spaced relation along a side edge of the die, and the tongues 32 of the end bead strips 23 register with the punches of a similar row or series of horizontally movable punches 35 extending in spaced relation across the ends of the die. The horizontally movable punches 34 and 35 are so arranged that when the ends of these punches are moved laterally into the die recess they will engage the tongues 30 and 32 and bend the same inwardly through the slots of the running board flanges. As shown in Figs. 2 and 6, the punches 34 and 35 are pivoted, respectively, to collars 37 and 38. The collars 37 are keyed to a rock-shaft 39 which is supported in bearings 39' and which extends along a side edge of the die recess, and similarly the collars 38 are keyed to rock-shafts 40 which are supported in bearings 40' and which extend transversely near the ends of the die recess. The rock-shafts 39 and 40 are connected together at their adjacent ends by the interengaging levers 41 and 42, so that upon rotation of the shafts 40 by the application of force to the levers 43 secured thereto, the rock-shaft 39 will be rotated to actuate the punches 34 simultaneously with the actuation of the punches 35.

The slide 26 which, as already indicated, is guided by the frame uprights 27, is adapted to be moved into cooperating position with the die 28, and into engagement with the running board placed in the recess of the latter by the operator. This slide is provided with a substantially rigid body member 43, which extends between the frame uprights 27 and may be constructed as a casting, or may be made up of parts welded or otherwise secured together, as shown in Figs. 4 and 5. A pressure plate 44 is loosely secured to the slide body 43, at spaced points by means of the studs 45 which are screwed into the pressure plate and are slidable in openings provided in the slide body. Coil springs 46 surrounding these studs resiliently press the pressure plate away from the slide body, so that when the slide is moved into engagement with the running board in the die recess, the pressure plate will engage the back of the running board with a firm but somewhat yielding pressure, and will accommodate itself to the running boards even though they may be slightly irregular in size or shape. The slide is also provided with a punch plate 47 which is movable relative to the slide body and the pressure plate, and which carries a plurality of vertical punches 48 secured in spaced re-

lation along a side edge thereof, and a plurality of vertical punches 49 secured in spaced relation across the ends thereof. Studs 49' which are secured to the punch plate and are 5 slidable in openings provided in the slide body 43, guide the movement of the punch plate relative to the slide body, so as to maintain these parts in proper relation at all times. Coil springs 50 surrounding the studs 49' tend to press the punch plate away from the slide body, so as to retract the vertical punches 48 and 49.

For moving the slide 26 toward the die 28 and into engagement with the running board arranged in the recess thereof, we provide a 15 main shaft 51 which is adapted to be driven by an electric motor 52 through suitable gearing 53. A pair of cams 54 secured to the shaft 51 engage the columns 55 of the slide body upon rotation of the shaft, and press the slide downwardly against the work. These 20 columns, as shown in Fig. 4, are secured to the slide body and extend through openings provided in the punch plate 47. If desired contact rollers 56 of appropriate diameter 25 may be provided at the upper ends of these columns to reduce friction between the latter members and the cams 54.

It will be seen from the arrangement thus far described that when the shaft 51 is rotated the cams 54 will lower the slide 26, causing the pressure plate 44 to engage the back of the running board body. Further movement of the slide in the downward direction causes the spring 46 to be slightly compressed, so that the running board will be firmly held in place in the die recess. These 35 springs and the relative movement provided between the pressure plate and the slide body enable the press to accommodate and operate upon the running boards regardless of variations occurring in the size or shape thereof.

At the ends of the slide 26 we provide 40 guide sleeves 57 in vertical alignment with the levers 43 of the rock-shafts 40. Vertical push rods 58 for actuating the rock-shafts are slidable in these sleeves and are guided thereby. When the slide is moved downwardly toward the die 28 the contact caps 58' at the lower ends of the push rods engage the levers 43, and upon further downward movement of the slide the push rods slide through the sleeves 57 without exerting any 45 pressure upon the levers 43. However, after the slide has reached the limit of its downward movement and the pressure pad 44 has firmly engaged the running board, the cams 59 engage the rollers 60 of the push rods 58 and move the latter downwardly to actuate 50 the levers 43. Movement of these levers causes the rock-shafts 40 and the rock-shaft 39 to be rotated in their bearings. The rotation of these rock-shafts causes the punches 55 54 and 35 to be moved into the die recess

to bend the tongues 30 and 32 of the bead strips inwardly through the corresponding slots provided in the running board flanges. Immediately after the horizontal punches have been actuated by the cams 59, the retracting springs 61 having opposite ends thereof secured to the rock-shaft levers 62 which extend downwardly through openings in the bed plate 25, cause the rock-shafts to be rotated in the reverse direction to retract the punches 34 and 35 from the slots of the running board flanges. 70

Upon further rotation, the shaft 51 causes the cams 63 to engage the rollers 64 of the columns 65 and to thereby press the punch plate 57 downwardly toward the slide body 43 against the action of the springs 50 interposed therebetween. The downward movement of the punch plate causes the punches 48 and 49 carried thereby to engage the 80 tongues 30 and 32 of the bead strips which, as explained above, have already been bent inwardly by the horizontal punches, and to bend or deflect the inner ends of these tongues downwardly so as to clinch them around the 85 edges of the slot openings, as shown in Figs. 4, 6 and 11 of the drawings.

Immediately after the cams 63 have moved the punch plate 47 downwardly, they release the rollers 64, whereupon the springs 50 move the punch plate upwardly away from the slide body thereby retracting the punches 48 and 49 out of engagement with the work. It will be understood, of course, that during the 90 period of time that the horizontal and vertical punches are being actuated by the cams 59 and 63, the cams 54 will retain the slide and the pressure plate 44 in their lowermost position, firmly holding the work in place in the die recess. It will also be seen from the 95 arrangement described that the horizontal punches 34 and 35 are actuated first by the cams 59 and are retracted by the springs 61 before the vertical punches are actuated by the cam 63. Likewise, the vertical punches 100 48 and 49 after having been actuated by the cams 63, are retracted by the springs 50 before the cams 54 allow the slide to be moved upwardly away from the work by the slide reTRACTING SPRINGS 66 and the counterweight 67. 105

In Fig. 12 of the drawings we have shown the shape or outline of the slide actuating cams 54, and in Fig. 13 we have shown the shape of the punch actuating cams 59 and 63, and also the angular position of the latter cams on the shaft 51 with respect to the cams 54. From these cam outlines and arrangements it will be readily seen how the slide is held in its lowermost or work-engaging position by the cams 54 during the time that 110 the horizontal punches and vertical punches are actuated in succession by the cams 59 and 63. 115

It should be noted that, as shown in Figs. 10 and 11 of the drawings, that the end 120

portion of each bead strip 23 which follows the curvature of the front flange 19, is provided with a flange-like tongue or extension 68. This extension must be bent around the edge 69 of the depending front flange 19, and to perform this operation simultaneously with the actuation of the vertical punches, we have constructed the corner punches 70 of special form, as shown in Figs. 7, 8 and 9, so that they will accomplish this result. These punches are pivoted at their upper ends to the punch plate 47 and each punch is provided near its lower end with a rounded shoulder portion 71. When the punch plate 47 is moved downwardly by the cams 63, this rounded shoulder portion will engage the inclined surface 72 of the pivoted pawl 73 and cause the punch 70 to be swung laterally upon its pivot as it descends. Each of these punches is also provided near its lower end with a depending relatively thin flange portion 74, and additionally, each punch is provided with a laterally extending ear portion 75 just above this flange portion. As the punch plate descends the flange portion 74 engages the extension 68 of the bead strip 23 and bends it downwardly around the edge 69. Simultaneously with its downward movement the punch 70 is deflected laterally by the engagement of the shoulder 71 with the inclined face 72, and this lateral movement causes the ear 75 to bend the extension 68 further around and under the edge 69 of the front flange. Continued movement of the punch plate in the downward direction causes the flange 74 of the punch 70 to engage the tongue 76 of the bead strip 23, which has already been bent inwardly by one of the horizontal punches.

The corner punches 70 are normally held in retracted position by means of coil springs 77 arranged in openings of the slide body. Upon upward movement of the punch plate 47, after the cams 63 have released the rollers 64, the springs 77 cause the punches 70 to be swung toward their retracted position so that the ears 75 will clear the edge 69 of the front flange of the running board when the slide is moved upwardly to release the work.

If the character of the work being performed is such that adjustment of either the slide or the punch actuating means should be desirable, such adjustment can be made by removing one or more pairs of the rollers 56, 60 and 64 and substituting other rollers of a slightly different diameter. It will readily be seen that if rollers of larger diameter are substituted for those shown, the slide will be moved closer to the die 28 and likewise the punches will be moved farther into the die recess. In addition to this, further adjustment of the actuating means for the horizontal punches can be made by removing the contact caps 58' of the push rods 58 and substituting other caps of different proportions.

If desired our press may be provided with a suitable limit switch or other control means, so that when the operator starts the press, the shaft 51 will make but one complete revolution and will then be automatically brought to a stop to permit the operator to remove the finished piece of work and substitute another piece to be operated upon by the press. 70

It will be seen from the arrangement of structure which we have described, that in addition to means for securely clamping and holding the work, our improved punch press is provided with sets of punches adapted to be actuated by cams in such a manner that first one set of punches will press portions of covering material through openings of a body, and thereafter the other set of punches will operate upon those same portions of the covering material to clinch the same and securely attach the covering material to the body. In other words, our punch press involves the use of sets of punches which have intersecting paths of movement, and which are actuated successively to operate on portions of covering material to thereby secure 90 the same to a body. 75

While we have illustrated and described the device of our invention in a detailed manner, it should be understood, however, that we do not intend to limit ourselves to the precise 95 details and arrangements of structure illustrated and described, but regard our invention as including such changes and modifications as to not involve a departure from the spirit of the invention and the scope of the 100 appended claims. 105

Having thus described our invention, we claim:

1. In apparatus of the character described, the combination of supporting means adapted to receive a body having a portion to which a metallic strip is to be applied, pressure pad means for holding said body against said supporting means, means for moving said pressure pad means into engagement with said body, a plurality of punches for pressing portions of said strip into strip-securing engagement with said body, and automatically operable means movable in timed relation with respect to the movement of said pressure 115 pad means for actuating said punches. 110

2. In apparatus of the character described, the combination of supporting means adapted to receive a body having a portion to which a metallic strip is to be applied, pressure pad means for holding said body against said supporting means, means for moving said pressure pad means into engagement with said body, a plurality of sets of reciprocable punches, for pressing portions of said strip into strip-securing engagement with said body, supporting means for said punches arranged so that the path of movement of one of said sets intersects the path of movement of another of said sets, and means for actuat- 125 130

ing said sets of punches successively in timed relation with respect to the movement of said pressure pad means.

3. In apparatus of the character described, 5 the combination of supporting means adapted to receive a body having a portion to which a metallic strip is to be applied, pressure pad means for holding said body against said supporting means, cam means for moving 10 said pressure pad means into engagement with said body, a plurality of punches, means supporting said punches for reciprocable movement for pressing portions of said strip into strip-securing engagement with said body, and cam means for actuating said punches while said pressure pad means is in engagement with said body.

4. In apparatus of the character described, 20 the combination of relatively movable platens adapted to press therebetween a body having a portion to which metallic covering is to be applied, a plurality of punches associated with one of said platens for pressing portions of said covering through openings of said body, a set of punches associated with the other of said platens for operating on the portions of said covering which have been pressed through said openings, and means for actuating said sets of punches in succession.

5. In apparatus of the character described, 30 the combination of relatively movable platens adapted to press therebetween a body having a bead portion to which metallic covering is to be applied, a plurality of punches associated with one of said platens for pressing portions of said covering through openings of said body, a set of punches associated with the other of said platens for operating on the portions of said covering which have been pressed through said openings, and cam means for actuating said sets of punches in succession.

6. In apparatus of the character described, 45 the combination of stationary and movable platens adapted to press therebetween a body having a portion to which metallic covering is to be applied, means for actuating the movable platen, a set of punches associated with the stationary platen for pressing portions of said covering through openings in said body, means for actuating said set of punches, a second set of punches associated with the movable platen for operating on the portions of said covering which have been pressed through said openings, and means for actuating said second set of punches.

7. In apparatus of the character described, 60 the combination of stationary and movable platens adapted to press therebetween a body having a portion to which metallic covering is to be applied, means for actuating the movable platen, a set of punches associated with the stationary platen for pressing portions of said covering through openings in said body, means including a rotatable shaft for actu-

ating said set of punches, a second set of punches associated with the movable platen for operating on the portions of said covering which have been pressed through said openings, and means for actuating said second set of punches.

8. In apparatus of the character described, 70 the combination of stationary and movable platens adapted to press therebetween a body having a portion to which metallic covering is to be applied, means for actuating the movable platen, a set of punches associated with the stationary platen for pressing portions of said covering through openings in said body, means for actuating said set of punches, a second set of punches for operating on the portions of said covering which have been pressed through said openings, mounting means for the second set of punches, said mounting means being carried by the movable platen and being movable relative thereto, and means for moving said mounting means to actuate said second set of punches.

9. In apparatus of the character described, 80 the combination of stationary and movable platens adapted to press therebetween a body having a portion to which metallic covering is to be applied, means for actuating the movable platen, a set of punches associated with the stationary platen for pressing portions of said covering through openings in said body, means including a rotatable shaft for actuating said set of punches, a second set of punches associated with the movable platen for operating on the portions of said covering which have been pressed through said openings, mounting means for the second set of punches, said mounting means being carried by the movable platen and being movable relative thereto, and means for moving said mounting means to actuate said second set of punches.

10. In apparatus of the character described, 90 the combination of relatively movable platens adapted to press therebetween a body having angularly disposed portions to which metallic strips are to be applied, sets of punches associated with one of said platens for pressing portions of said strips through openings in the respective body portions, means for actuating said sets of punches including angularly disposed rotatable shafts, and means for rotating said shafts.

11. In apparatus of the character described, 100 the combination of relatively movable platens adapted to press therebetween a body having angularly disposed portions to which metallic strips are to be applied, sets of punches associated with one of said platens for pressing portions of said strips through openings in the respective body portions, means for actuating said sets of punches including angularly disposed rotatable shafts, and interengaging means operably connecting said rotatable shafts.

12. In apparatus of the character described, the combination of stationary and movable platens adapted to press therebetween a body having a portion to which a
5 metallic strip is to be applied, cam means for actuating the movable platen, a set of punches associated with one of the platens for pressing portions of said strip through openings in said body, cam means for actuating said set of punches, a second set of punches associated with the other of said platens for operating on the portions of said strip which have been pressed through said openings, and cam means for actuating said
10 second set of punches.
15

In testimony whereof, we hereunto affix our signatures.
